UNITED STATES PATENT OFFICE.

GIUSEPPE MENARINI AND ATTILIO EMANUELE, OF ROME, ITALY.

DEVICE FOR PRACTISING IN SHOOTING WITHOUT PROJECTILES.

1,031,566.

Specification of Letters Patent.

Patented July 2, 1912.

Application filed March 29, 1910. Serial No. 552,252.

To all whom it may concern:

Be it known that we, GIUSEPPE MENARINI and ATTILIO EMANUELE, both subjects of the King of Italy, and residing at Rome, in the 5 Kingdom of Italy, have invented a new and useful Device for Practising in Shooting Without Projectiles, of which we declare the following to be a full, clear, and exact description, such as will enable others skilled 10 in the art to which it appertains to make and use the same.

The object of the present invention is a device destined for simulating, when exercising in shooting without projectile, the effects 15 which the shot itself would have produced, if bullet cartridges had been made use of.

This effect is obtained: (a) by connecting with the rifle, in the way described herein- 20 after, a rod, which always keeps itself parallel to the axis of the barrel, forming a rigid system with the sighting line in all the movements which the shooter imparts to the rifle, while he is sighting on the object 25 which he intends to hit; (b) by disposing a paste-board target of suitable size kept by a frame in front of an end of the said rod; (c) by causing a snapping lock controlled 30 by the firing pin to act, which lock, when the shooter has pressed upon the trigger, allows the frame with the paste board target to advance toward the end of the indicating rod, with which it comes into contact in the moment in which the projectile would have 35 left the barrel, if a bullet had been really fired, so that the exact position of the point of the rod and therefore of the direction of the sighting line in this very moment is recorded on the aforesaid pasteboard by means 40 of a little hole, which is produced through the above mentioned contact. As the deviations, which are to be recorded, are generally very small, so in practice the apparatus mentioned had to be completed with a multiplying device, which amplifies the angles 45 of deviation of the indicating rod and allows therefore of the value of the deviations themselves being appreciated more exactly.

50 An advantage of great practical value of the above mentioned apparatus and which differentiates the same substantially from the other apparatus for verifying the shots hitherto known, consists in the fact that the

shooting can take place without or with cartridges, no matter whether the cartridges are blind ones or containing bullets, and in any position from which it can be shot, without compelling the soldier to accommodate himself to the support sustaining the rifle, which also in this case can freely be kept in the arm and moved in any direction, without hindering the soldier in any way in these movements.

The annexed drawing by way of example 65 shows diagrammatically an apparatus for simulating the effects of the shots without projectile according to the present invention, viz.

Figure 1 shows the complete apparatus 70 seen in elevation; Figs. 2, 3 and 4 show on a larger scale the details of two of the gimbal suspensions used in the apparatus and of the snapping lock. Fig. 5 shows the transverse section of the bar which is fastened to 75 the rifle. Fig. 6 is a lateral view of the connection between the gun and the tube which transmits the movement to the subtarget, Fig. 7 is a plan of the same part, Figs. 8 and 9 show in section and back view respectively a detail of this connection, and Fig. 10 is a view of the device for producing the transverse movement of the subtarget.

Upon the plane —1— of a metallic base is applied in the central portion a metallic 85 support of cast iron or bronze —3—. In this support rest the pivots —3— projecting laterally in the way of trunnions from a rocking plane —4— consisting also of a long and narrow metal plate having a sufficient 90 thickness to insure a perfect rigidity and which can also be swung about said pivots. One of the ends of the plane —4— carries a toothed sector —5—, which engages with a toothed pinion carried by a journal —6— 95 mounted on bearings of another support —7— provided on the plane —1—. By means of a hand-wheel —8— carried by the shaft —6— the latter can be caused to rotate and therefore the inclination of the 100 plane —4— can be altered with respect to the horizontal line. On the plane —4— is a gimbal suspension formed by a frame —9—10—, on which is mounted a vertical axis —11— which can revolve and carries a 105 forkshaped support —12—, between the arms of which is disposed the horizontal axis —13— which can also revolve and supports

at the center of gravity a hollow rod —14—, inside which four grooved wheels —15— 15"—16"—16"— are mounted. The two first wheels are placed at such a distance 5 from each other that the space between their axes, increased by the diameter of the wheel measured at the bottom of the groove, corresponds to the distance interceding between two holes —17'—17"— bored vertically in the thickness of the bar which at the center 10 has another hole —18—. These holes are not cylindrical but conically expanding from both sides and the centers of their cross sections at the narrowest part are upon a 15 straight line passing through the center of suspension of the rod —14—, which suspension point coincides with the center of the cross section in the narrowest part of the central hole —18—. A bar 19 is provided 20 with attachments of any kind whatever (not shown in the drawings) which serve to fasten this bar to the rifle between the locking stud for the bayonet and the connecting band. This bar has toward its 25 ends two holes 20' and 20" by means of which two non-extensible wires 21', 21" are fixed to it. The distance between the centers of the two holes 20', 20" is exactly the same as the distance between the centers of 30 the two holes 17' and 17". The two wires 21' and 21" pass through the holes 17', 17" and for a quarter of a winding around the pulleys 16' and 16" respectively, to join an 35 elastic string 22 to which they are attached and which in consequence strains them in an equal measure. This string is attached by means of a hole 23 to the bar 19, the center of the hole 23 being at equal distances from the centers of the holes 20' and 20" respectively. 40

The wires —21'—21"— and the string —22— are not invariably fixed to the bar —19—, but they are connected to same by means of elastic clamps —24— (Fig. 5), 45 which are automatically released in the case of the tension of the wires becoming too strong.

From what has been said it will easily be understood that the hollow rod —14— and 50 the bar —19— form two sides of a movable parallelogram, the other two sides of which, of variable length are formed by the wires —21'—21"— which are stretched and pass through the holes —17'—17"— and the 55 points of attachment —20'—20"— of the wires to the bar —19—. In case the axis of the gun barrel deviates by a certain angle in a vertical plane, the line which passes through the centers of the holes 17' and 17" 60 deviates in the same way. If the axis of the gun barrel deviates by a certain angle in a horizontal plane, the mentioned parallelogram would tend to get deformed as the two lines passing through the centers of the 65 holes 20' and 20" and 17' and 17" would

have a tendency to place themselves in different planes. The horizontal components of the tension of the wires 21' and 21" transmitted to them in an equal measure by the elastic string 22, however, tend to displace the hollow rod 14 so as to bring the line which passes through the center of the holes 17' and 17" back to place itself also in this case in the plane of and parallel to the line which passes through the center of the 75 holes 21' and 21".

In practice it will be convenient to give to the bar —19— the same weight of the ramrod of the rifle so that, if the ramrod is withdrawn before applying the device to the rifle, the weight of the latter remains unvaried and the shooter can still handle the rifle in the same way as if it were perfectly free. Therewith the first portion of the device could be considered complete; in fact a 80 device thus formed can advantageously be utilized in many instances; however, as, when the results of the shooting must be recorded, also the small deviations have to be considered, so it is preferable to provide 85 also a multiplying device for amplifying the angle of deviation described by the hollow rod —14—.

A very convenient multiplying device is for instance that shown in the drawing and 90 which is formed in the following way: The rod —14— carries at its front end two vertical pivots —26—, around which can revolve a ring —27— which is provided with two horizontal pivots —28—. Around these 100 pivots —28— revolves another larger ring —29— which encircles the first one and below supports a rectangular or circular frame —30—. To balance the weight of this system of rings —27—29—, which form a perfect gimbal suspension, the rod —14— at 105 its rear end is provided with a counterweight —31—, the position of which can be regulated in such a way as to keep perfectly balanced the rod —14—. On the plate —4— is provided a second support —32—, which carries a vertical frame —33— forming another gimbal suspension, which can be turned around a fixed point —34— and supports a needle —35—. The needle —35— passes through the rectangular ring —30—, with which it is connected by means of two horizontal pivots —36—, so that in all positions the axis of the needle —35— passes always through the center 110 —37— of the frame —30—. The effect of 115 this disposition is that the needle —35— repeats amplified the movements of the fore end of the rod —14— and the amplifying power can be regulated at will by approaching or moving away more or less the position of the points —34—37—.

In front of the point of the needle is placed a frame —38— into which is introduced a pasteboard on which is already 120 125 130

marked the point which corresponds to that chosen for the sighting. The frame —38— can be moved transversely to the direction of the length of the plate —4— and is carried by a slide —39— movable in the longitudinal direction. The transverse movement of the frame is produced by means of an adjusting screw —40—, as is shown in Fig. 10. The slide 39 is connected to the frame 38 by means of a frame 57 which has two rectangular openings 58 and two lugs 59 which receive the screw 40. Through the openings 58 pass two other lugs 60 which are provided with a threaded hole 15 to receive the said screw 40. By turning this screw one obtains a transverse displacement of the frame 38. The longitudinal movement of the slide is obtained by means of a spring —41— which normally is kept 20 compressed by a catch —42— which prevents the forward motion of the slide. When the catch is raised, the spring pushes forward the slide which advances for such a distance as to bring the paste board target 25 into the position where it is pierced by the point of the needle. During this forward movement however the slide, on account of the kinetic energy stored up in it, goes beyond the position in which the spring is in 30 equilibrium, thus slightly straining the said spring. In consequence, as soon as the hole in the target has been made, the slide drawn by the spring moves backward slightly so as to disengage the point of the needle 35 from the hole which it has produced in the target. The unlocking of the slide through the raising of the catch can be produced in any way; for instance electrically; but a simple manner consists in connecting the 40 catch with the piston —43— of a small cylinder —44—, into which the compressed air is introduced through a small tube of india-rubber. Said tube comes from the body of a pump, the piston of which is moved by the 45 firing pin of the rifle in firing the shot as is illustrated by the Figs. 6, 7, 8 and 9 which show by way of example this part as applied to a modern gun, that is to say, to a gun as used in Italy. The cylinder 47 of a small 50 piston carries laterally a lug 48 with the holes 49 and 50. One unscrews the button 51 of the firing pin, and introduces the said firing pin into the hole 49 and a pin for holding up the button 51 (which pin is not 55 shown in the drawings) into the hole 50. One then screws the button of the said firing pin on again. In the cylinder 47 slides tightly a piston 52 which is provided with a counter spring 53. The rod 54 of this piston is provided along its axis with a hole and carries laterally a projection 55 which enters the notch 56 of the wooden gun stock. The end of the rod 54 is threaded on its outside and on this screw is fixed an india rubber tube 57 whose other end enters the hole 46

of the piston 43 (Fig. 4). On the gun being loaded, the cylinder 47 connected with the firing pin moves backward while the piston 52 remains in place held back by the projection 55 engaging in the notch 56 through the action of the spring 53. On the gun being discharged, the firing pin moves abruptly and violently forward; in consequence, also the cylinder 47 drawn by the spring 53 moves forward without altering in any way 70 the working of the spring of the firing pin. The air compressed between the cylinder 47 and the piston 52 which is immovable flows out through the rod 54 and the tube 57 and actuates as has been said, the piston 43. 75

The piston, the rod —45— of which rests underneath the catch, is normally lowered and kept in this position through its own weight. The compressed air, which arrives in the cylinder through the hole —46—, 80 raises the same so as to disengage the slide. In the moment in which the slide is left free, the piston passes beyond a large hole 61 provided in the wall of the cylinder so that the compressed air escapes from the said 85 hole and the firing pin does not need to overcome any further resistance, as the same has no further volume of air to compress. As soon as the compressed air has ceased to act beneath the piston 43 and has escaped, 90 as has been said, through the large hole 61, and after the unlocking of the slide has been effected, the piston will be drawn downward by its own weight so as to close the hole 61. This downward movement of the piston 100 however would be impeded by the air which, without a possibility of escape, is stored up beneath the piston in the lower part of the cylinder 44. To prevent this inconvenience, the cylinder has been provided at a point of 105 the chamber which the piston, when in its lowest position, will not obstruct, with a hole which is so small that the quantity of compressed air escaping through it is not sufficiently large to prevent the upward 110 movement of the piston, but which on the other hand is large enough to allow the air which would prevent the piston from descending, to escape so that the piston may completely descend and bring the catch 115 again in such a position as to be able to again lock the slide as soon as the same has again been brought into the operative position by carrying it back.

The working of the device will now easily 120 be understood: After having placed the metallic base —1— in such a way that the rod —14— lies in the vertical plane containing the point which is to be sighted at, the bar —19— is fastened to the rifle and the latter 125 rests upon a sighting frame and is directed with the greatest care toward the above mentioned point. After having secured a perfect sighting by working the hand wheel —8— and the adjusting screw —40—, which 130

produces the transverse displacement of the frame —38—, the center already marked on the pasteboard is brought in a position corresponding exactly to the point of the needle 5 —35—. When this has been done, the rifle can be taken off the frame and given to the shooter. If he directs the sighting line again on the same point, on which the sighting was performed with the rifle on the 10 frame, the point of the needle —35— will come again in correspondence with the center of the pasteboard, otherwise it will mark a different point and, if the slide has been placed in the operative position, when pushing 15 the trigger, on the pasteboard will be produced a hole the distance of which from the center will indicate on the selected scale the extent of the deviation which the projectile would have undergone, if a bullet had 20 been shot. As the piercing of the pasteboard has to take place in the very moment in which the projectile leaves the barrel, the transmission of the motion to the catch is regulated in such a way that the pasteboard 25 touches the point of the needle just in the said moment.

Having now fully described this our invention and how the same is to be carried out, we declare that what we claim is:

In devices for ascertaining the effects of 30 the fire in practising shooting without projectile the combination of: a gimbal suspension, a movable rod held by said suspension, grooved rollers on said rod; two flexible and inextensible strings running on said 35 rollers and having one of their ends fastened to the rifle, an elastic string joining the other two ends of the inextensible strings and fastened at the other end to a point of the rifle, so as to form a deformable parallelogram two sides of which are the sighting line and the movable rod, as illustrated in the drawings and for the purposes set forth in the specification.

In testimony whereof we have signed our 45 names in the presence of two subscribing witnesses this 15th day of March 1910.

GIUSEPPE MENARINI.
ATTILIO EMANUELE.
